US0D1096753S

(12) **United States Design Patent** (10) **Patent No.:** **US D1,096,753 S**
(45) **Date of Patent:** **** Oct. 7, 2025**

(54) **SPLIT KEYBOARD**

(71) Applicant: **Cloud Nine Ergo LLC**, Boulder, CO (US)

(72) Inventor: **Blake Olson**, Superior, CO (US)

(73) Assignee: **CLOUD NINE ERGO LLC**, Boulder, CO (US)

(**) Term: **15 Years**

(21) Appl. No.: **29/935,067**

(22) Filed: **Mar. 29, 2024**

(51) LOC (15) Cl. **14-02**

(52) U.S. Cl.

USPC **D14/393**

(58) **Field of Classification Search**

USPC D14/247, 320, 331, 333, 338, 346,

(57) **CLAIM**

The ornamental design for a split keyboard as shown and described.

DESCRIPTION

FIG. 1 is a perspective view of the split keyboard;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines shown in the figures illustrate portions of the split keyboard that form on part of the claimed design. The dash-dot-dash broken lines represent boundaries of the claimed design and form no part thereof.

1 Claim, 5 Drawing Sheets
